US0D1099556S

(12) United States Design Patent (10) Patent No.: US D1,099,556 S
(45) Date of Patent: * Oct. 28, 2025

(54) SHEET MATERIAL

(71) Applicant: CARTIER INTERNATIONAL AG,
Steinhausen (CH)

(72) Inventor: Fabrice Colin, Paris (FR)

(73) Assignee: CARTIER INTERNATIONAL AG,
Steinhausen (CH)

() Term: 15 Years

(21) Appl. No.: 29/901,341

(22) Filed: Aug. 31, 2023

(30) Foreign Application Priority Data

Mar. 2, 2023 (WO) WIPO129488

(51) LOC (15) Cl. 05-05

(52) U.S. Cl.

USPC D5/30; D5/59

(58) Field of Classification Search

USPC ... D5/1, 3, 4, 5, 7, 8, 10, 11, 12, 19, 20, 22,

(57) CLAIM

The ornamental design for a sheet material as shown and described.

DESCRIPTION

FIG. 1 is a perspective view of a sheet material showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines show portions of the article that form no part of the claimed design.

1 Claim, 7 Drawing Sheets
